Primary Examiner — Sandra S Snapp*Assistant Examiner* — Katherine Glennon(74) *Attorney, Agent, or Firm* — Bayramoglu Law Offices LLC(57) **CLAIM**

The ornamental design for a watch, as shown and described.

DESCRIPTION

FIG. 1 is a front elevation view of a watch showing the new design;

FIG. 2 is a rear elevation view thereof;

FIG. 3 is a left elevation view thereof;

FIG. 4 is a right elevation view thereof;

FIG. 5 is a top plan view thereof; and,

FIG. 6 is a bottom plan view thereof.

The broken lines in the figures illustrate portions of the watch that form no part of the claimed design.

1 Claim, 6 Drawing Sheets(56)
